UNITED STATES PATENT OFFICE

EDWIN B. STIMPSON, OF BROOKLYN, NEW YORK.

MACHINE FOR ORNAMENTING LEATHER.

SPECIFICATION forming part of Letters Patent No. 375,105, dated December 20, 1887.

Application filed June 8, 1887. Serial No. 240,572. (No model.)

To all whom it may concern:

Be it known that I, EDWIN B. STIMPSON, of Brooklyn, in the county of Kings and State of New York, have invented a new and useful Improvement in Machines for Ornamenting Leather, of which the following is a specification.

My invention relates to a machine for ornamenting leather by impressing the leather to form recesses on one side and corresponding raised ribs or projections on the other side, the recesses being subsequently filled with a plastic filling to maintain the full projection or prominence of the ribs or raised portions.

In my improved machine are comprised, in combination with a sliding mandrel and an oppositely-arranged bed, dies which are carried, respectively, by the mandrel and bed, and one of which has surface portions of different configuration, and one of which is movable laterally to bring the portions of different configuration on one die into and out of coincidence with the other die, and the lower die is also movable to expose it for the reception of material to be operated on; and I furthermore employ stops for limiting the lateral movement of the die or dies and insure their correct position for successive operations. I also provide a connection through which the mandrel is operated from a lever or other device, and which is adjustable in length, so as to vary the range of movement of the mandrel to suit dies of different thickness.

The invention consists in novel combinations of parts in a machine, as hereinabove referred to, and hereinafter particularly described, and pointed out in the claims.

In the accompanying drawings, Figure 1 represents a sectional elevation of a machine embodying my invention. Fig. 2 is a sectional elevation in a plane at right angles to Fig. 1. Fig. 3 is a horizontal section upon about the plane indicated by the dotted line $x\ x$, Fig. 1. Fig. 4 is a section, corresponding to Fig. 1, of a portion of the mandrel, the supporting-bed, and the dies, illustrating a slight modification of my invention. Fig. 5 is a front elevation of the parts shown in Fig. 4. Fig. 6 is a plan of the bed and the die supported thereon corresponding to the modified construction shown in Figs. 4 and 5. Fig. 7 is a gage or pattern

which may be employed for cutting or trimming the ornamented leather. Fig. 8 is a sectional view showing the method of using such gage, and Fig. 9 is a view of a toe-cap.

55

Similar letters of reference designate corresponding parts in all the figures.

A designates a suitable frame, wherein is guided a mandrel, B, here shown as locked in the frame to prevent its turning by a feather or spline, b, entering the groove b'. This mandrel B may be operated by means of a lever, C, fulcrumed at c, and a link or connection, C', which is composed of two end portions or eyes connected by a portion having right and left screw-threads, and which may be turned to increase or diminish the length of the connection, thereby giving the mandrel B a lower or higher range of movement.

Opposite the mandrel B is a supporting bed, A', and upon the mandrel B and the bed A' are dies D D'. By the reciprocation of the mandrel B leather introduced upon the die D' is pressed by means of the opposite die to give it the form desired. As here represented, the die D is fixed upon the mandrel B and has a fluted or grooved portion, d, and a plain or flat surface portion, d', while the die D' has a grooved or fluted portion, d'', corresponding to the portion d of the die D. One of the two dies D D' is movable laterally to bring either the surface d or d' of the die D into and out of coincidence with the surface d'' of the die D'; so that after the leather has been operated upon by the portion d d' of the two dies to impress in it ribs or ridges the portion d' may be brought into coincidence with the portion d'' of the lower die, D', and by again depressing the mandrel a piece of covering fabric—such as paper or cloth—may be cemented and pressed firmly upon the leather.

In this example of the invention the lower die, D', is alone movable laterally, and it is also movable to a further extent than described, to afterward expose the die D' so that leather may be placed upon it, and so that after leather is pressed by the portions d d' the impressed leather may be exposed to enable filling material to be placed in the recesses or depressions before the covering fabric is cemented thereon. In the operation of these parts the die D', having a piece of leather upon it, is brought to the position

shown in Fig. 1, and such position is definitely fixed by a spring, d^3 , which is secured to the die D' and has a prong or projection entering a notch or recess, d^4 , in the bed A' , as shown 5 best in Fig. 2, and also in Fig. 3. The lower die, D' , is locked in position, with its portion d^2 immediately opposite the portion d of the upper die, and by depressing the mandrel B the leather, by the action of the dies D D' , is 10 formed with grooves or depressions. The die D' is then moved laterally outward to an extent limited by a projection, d^5 , on the die striking against the inner edge of the bed A' , and the filling material, which may consist of 15 cords, but which preferably consists of plastic material—such as gum, dextrine, or paper-pulp—is placed in the grooves or depressions in the leather. The die D' is then slid inward to a greater extent than before, and until its inner 20 edge strikes against the press-frame A, as shown at d^6 by dotted lines, and in this position the plain surface d' of the die D is in coincidence with the surface d^2 of the die D' , and by depressing the mandrel B a piece of covering 25 fabric—such as paper or cloth—is secured by cement and pressure upon the leather and over the filling material. By means of a templet, S, which may have a ridge or shoulder, s , to fit against the outermost rib or ridge in the 30 leather, and which is applied to the leather, as shown in Fig. 8, a gage is afforded for trimming off the edge of the leather.

In the example of my invention shown in Figs. 4, 5, and 6 the die D' , which has the 35 fluted or grooved portion d^2 , as before described, is supported upon the bed A' ; but the bed is pivoted at the end d^7 , so that it may be swung outward laterally, as shown by dotted lines in Fig. 6, and it may be retained in 40 definite position by a spring-catch, d^8 , entering a notch, d^9 , in the free end of the bed, and by a stop-pin, d^{10} , secured in the bed. The upper die, D , in this example of the invention has the portions d d' of different configuration, 45 as before described, and slides in a channel or dovetailed recess, e , in the stock plate or piece E, secured to the mandrel B. It is provided with a handle, e' , whereby it may be slid laterally, and its movement toward the 50 left hand of Fig. 4 is arrested by an upturned finger, e^2 , which strikes against the edge of

the plate E, and its movement toward the right hand of Fig. 4 may be limited by the said finger e^2 striking against the frame A. The lateral movement of the die D in this example of the invention provides for bringing either of the portions d or d' into coincidence with the portion d^2 of the lower die, D' , and the swinging movement of said lower die provides for exposing such die to receive the material upon it, and to permit of the filling of the recesses or depressions formed by the parts d d' of the dies. It will be obvious that although I have shown in this example of my invention dies for producing substantially 60 parallel ribs or ridges, the dies may be formed to impress the leather in any other ornamental shapes. 65

What I claim as my invention, and desire to secure by Letters Patent, is—

1. In the herein-described machine for ornamenting leather, the combination, with a sliding mandrel and an oppositely-arranged bed, of dies carried, respectively, by the mandrel and bed, and one having surface portions 70 of different configuration, and one of which is movable laterally to bring the portions of different configuration on one die into and out of coincidence with the other die, and the lower die being also movable to expose it for 75 the reception of material to be operated on, and stops for limiting the lateral movement of the die or dies and insuring their correct position for successive operations, substantially as herein described. 80

2. In the herein-described machine for ornamenting leather, the combination, with a sliding mandrel and an oppositely-arranged bed, of dies carried, respectively, by the mandrel and bed, and one having surface portions 90 of different configuration, and one of which is movable laterally to bring the portions of different configuration on one die into and out of coincidence with the other die, stops for limiting such lateral movement, and a connection, adjustable as to length, through which the mandrel is operated, substantially as herein 95 described.

EDWIN B. STIMPSON.
